UNITED STATES PATENT OFFICE.

JOHN ZSILAVETZ, OF SOUTH BETHLEHEM, PENNSYLVANIA.

SHIP'S TABLE.

1,088,118.

Specification of Letters Patent.

Patented Feb. 24, 1914.

Application filed October 6, 1913. Serial No. 793,638.

To all whom it may concern:

Be it known that I, JOHN ZSILAVETZ, a subject of the King of Hungary, residing at South Bethlehem, in the county of Northampton and State of Pennsylvania, have invented certain new and useful Improvements in Ships' Tables, of which the following is a specification.

This invention relates generally to tables, 10 and particularly to one adapted for use upon sailing or steam vessels.

The object of the invention is, in a ready and practical manner, so to support the table from the deck or floor as to cause it always and automatically to maintain a horizontal position irrespective of the slant or angle assumed by the deck due to the action of the waves.

With the above and other objects in view, 20 as will appear as the nature of the invention is better understood, the same consists in the novel arrangement and combination of parts of a self-leveling table, as will be hereinafter fully described and claimed.

25 In the accompanying drawing, forming a part of this specification and in which like characters of reference indicate corresponding parts: Figure 1 is a view in vertical longitudinal section through a self-leveling table constructed in accordance with the present invention. Fig. 2 is a horizontal section taken on the line 2—2, Fig. 1, and looking in the direction of the arrows thereon. Fig. 3 is an enlarged fragmentary detail view, 30 partly in section, showing the manner in which the legs of the table are cushioned. Fig. 4 is a transverse sectional view taken on the line 4—4, Fig. 1, and looking in the direction of the arrows thereon. Fig. 5 is 35 a sectional detail view, on an enlarged scale of a part of the apparatus.

Referring to the drawings, 1 designates the top of the table, 2 one of the sides thereof, 3 the ends, and 4 the legs. These parts 45 may be of the usual or any preferred construction and therefore need no further description.

Secured in any suitable manner to the deck or floor B are four cylinders or tubes 50 5, each housing a coiled spring 6, the lower whirl of each of which bears upon the bottom 7 of the cylinder, the upper whirl being engaged by an ovoidal shaped plunger head 8, one of which is carried by each of the 55 legs, and is of sufficiently less diameter than the bore of the cylinder to permit the table

to meet any angular spacing without any binding action occurring between the head and the cylinder. Secured to the under side of the table top is an eye bolt or hanger 9 that is engaged by one end of a link 10, the other end of which engages with an eye-bolt 11 carried by a boxing 12 in which are disposed a plurality of balls 13 that are normally spaced apart a sufficient distance to permit free rolling action, the box, counterweights 13, and link 10 forming in effect a poising device. Secured to the under side of the box adjacent to each end is an eye-bolt 14 and 15 respectively, and secured in a bracket 16 arranged below the center of the box is a grooved sheave 17, the sheave being provided with two grooves that are separated by a peripheral flange 18. Secured to the deck or floor are two other standards 19 and 20, each of which carries a sheave 21 and 22 respectively. The sheaves 17, 21, and 22, are engaged by ropes or chains 23 and 24, the rope 23 having one end secured in the eye-bolt or hanger 14, 60 thence turned once around the sheave 17 toward the left hand, thence passed around the sheave 21 and has its free end secured to an eye bolt or a hanger 25 secured to the under side of the table top adjacent one end. The rope 24 has one end secured in the eye-bolt or hanger 15, thence turned once around the sheave 17 toward the right hand, 65 thence passed around the sheave 22, and has its free end secured to an eye bolt 26 secured to the under side of the table top adjacent to the end opposite the eye bolt 25.

From the construction described, it will be seen that as the vessel rolls, the weight box will be swung by the vessel's motion, 95 and thus operate on either of the ropes or cables 23 or 24 to correct the inclination of the table and restore it and maintain it in a horizontal plane, the springs 6 in the cylinders 5 serving to cushion the table, so that there will be no jars or vibrations present, 100 no matter how violently the vessel may be rocked.

In order to meet every contingency that might arise, say where a sea of unusual 105 roughness is encountered, and to prevent dangerous tilting of the table, supplemental checking means are provided which consists of four chains 27 and 28, each of these chains being secured at one end to an eye bolt 29 and 30 respectively secured to the deck, and at their other ends to eye-bolts 31

and 32 secured to the inner sides of the legs adjacent the upper ends, the intermediate portion of the chains being passed beneath grooved sheaves 33 supported by standards 34 secured to the deck. Normally, the chains are out of engagement with the sheaves 33, and only contact therewith when the vessel makes an unusually heavy lurch, and one which would tend or might tend to render the co-action between the legs and the cushioning springs non-effective.

From the foregoing description it is seen that although the improvements of the present invention are simple in character, they will be thoroughly efficient in securing the object sought, and wherein, further, by the manner of arrangement of the parts, liability of derangement in use, is reduced to the minimum.

What I claim as new and desire to secure by Letters Patent is:—

1. A table having its legs cushioned, a pendulous counter-weight carried by the top of the table, sheaves secured adjacent to each end of the table and at its center, and cables secured to the ends of the counter-weight and to the table top and passing around the sheaves.

2. A table having its legs cushioned, a

pendulous counter-weight carried by the top 30 of the table, sheaves secured adjacent to each end of the table and at its center, and cables secured to the ends of the counter-weight and to the table top and passing around the sheaves, in the same direction around the 35 terminal sheaves and in a reverse direction around the intermediate sheaves.

3. The combination with a support, of a plurality of cylinders secured thereto, coiled springs arranged within the cylinders, a 40 table having legs provided with terminal rounded heads to bear upon the springs, a pendulous counter-weight secured to the under side of the table, sheaves arranged adjacent each end of the table, and beneath 45 the center thereof, and cables secured to the counter-weight and passing around the sheaves and secured to the under side of the table top and passing around the sheaves in the same direction around the terminal 50 sheaves and in reverse directions around the intermediate sheaves.

In testimony whereof I affix my signature in presence of two witnesses.

JOHN ZSILAVETZ.
